**BIASED MAGNETICALLY OPERATED
 ELECTRICAL SWITCHES**

Henry D. Brunette, Milwaukee, and Roy Hyink, Wauwau-tosa, Wis., assignors to Cutler-Hammer, Inc., Milwaukee, Wis., a corporation of Delaware
 Filed Apr. 5, 1963, Ser. No. 270,854
 5 Claims. (Cl. 317—155)

This invention relates to magnetically operated switches and relays having operating bias applied electromagnetically.

It is often desirable to vary the pick-up and drop-out voltages and currents of the device to suit a particular application. In the case of reed switches and relays utilizing reed switches, the operating voltages are adjusted by means of electromagnets or permanent magnets in the vicinity of the reed switches to provide a steady biasing flux. However, the application of a biasing magnetic flux in the usual manner affects simultaneously and similarly both the pick-up and drop-out currents. It is difficult to vary the pick-up and drop-out currents independently or to adjust the difference between these currents.

It is therefore an object of this invention to provide biasing means for magnetically operated switches by which the pick-up and drop-out points may be varied independently and the difference between these points may be selectively adjusted.

It is a further object of this invention to provide such a biasing means whereby the operation of the switch can be made dependent upon the polarity of the actuating flux or voltage.

These objects are accomplished by the application to a magnetically operated switch of a pulsating unidirectional biasing flux, the characteristics of which may be selectively adjusted to obtain the desired operating characteristics for the switch.

Other objects and advantages of this invention will become apparent upon reference to the following description and accompanying drawings.

While the devices hereinafter described are adapted to fulfill the objects stated, it is to be understood that it is not intended that the invention be confined to the particular embodiments disclosed since they are susceptible of various modifications without departing from the scope of the claims.

Referring to the drawings:

FIGURE 1 shows an electromagnetic switching device which may be used in the invention hereinafter described and claimed;

FIG. 2 shows a second version of electromagnetic device which may be incorporated in the present invention;

FIG. 3 is a graph of typical operating curves for prior art devices which is useful in the explanation of the operation of this invention;

FIG. 3a is a diagram of a circuit for applying a bias voltage to obtain the curves shown in FIG. 3;

FIG. 4 is a graph of operating curves for a device incorporating the present invention;

FIG. 4a is a diagram of a bias supply circuit which, when applied to the devices of FIG. 1 or FIG. 2, forms an embodiment of the present invention and which yields the curves shown in FIG. 4;

FIG. 5 is a graph of another set of curves for a variation of the invention; and

FIG. 5a is a diagram of a variation in bias supply circuitry, the operating curves of which are illustrated by FIG. 5.

In FIG. 1 there is shown an electromagnetic device comprising a reed switch 2, a bias coil 4, a magnetic shield 6 and an electromagnet 8. Reed switch 2 is of conventional construction having a sealed gas filled glass

envelope 2a. The magnetic reeds 2b and 2c are attached, respectively, to terminals 2d and 2e which are sealed in the ends of glass envelope 2a. Reed switch 2 is preferably shown with reed 2b shorter than reed 2c which places the contact gap toward the lower end of the switch. When magnetic flux of sufficient intensity is impressed upon switch 2, magnetic reeds 2b and 2c are mutually attracted and the gap between them closes to complete an electric circuit between terminals 2d and 2e. Exterior conductors (not shown) may be attached to terminals 2d and 2e.

Bias coil 4 surrounds reed switch 2 and comprises a single continuous electrical wire winding 4a covered by electrical insulating material 4b and having terminals 4c. Surrounding the lower end of coil 4, there is a shield 6 made of magnetic material which serves to shield the lower end of switch 2 from magnetic flux sources other than those directly below terminal 2d.

Reed switch 2 is actuated by flux from a separate electromagnet 8 having a magnetic core 8a, a coil 8b and terminals 8c. A signal current applied to terminals 8c serves to energize electromagnet 8.

FIG. 2 illustrates a variation of the electromagnetic device of FIG. 1. Certain elements of this second form are, for the sake of simplicity, given reference numerals identical to those of their equivalents in the first form illustrated in FIG. 1. Reed switch 2 is in this variation surrounded by two coils, a bias coil 4 similar to that of FIG. 1 and a signal coil 10 having a winding 10a, terminals 10b and an electrically insulating cover 10c. Signal coil 10 serves the same function as electromagnet 8 of FIG. 1 in that coil 10 provides the actuating flux for reed switch 2 when a signal current is applied to terminals 10b.

Three sets of curves, one for each of three types of biasing current, are illustrated in FIGS. 3a, 4a and 5a. The pick-up and drop-out curves, labeled respectively PU and DO are drawn on graphs of signal current (in milliamperes) versus bias current in milliamperes. It may be assumed that the direction of signal current is defined as forward when its effect is additive to the biasing flux and is defined as reverse when its effect opposes the biasing flux. FIGS. 3b, 4b and 5b show bias current supply circuits which will produce the results illustrated by the corresponding curves of FIGS. 3, 4 and 5.

FIG. 3a illustrates the operating characteristics of prior art devices and is useful in describing by contrast the operation and advantages of the present invention. Curves of the type shown in FIG. 3a are obtained from biased relays having an unfluctuating biasing force such as that provided by winding 4 when supplied by a source 12 of steady D.C. as shown in FIG. 3b. Steady D.C. from source 12 is applied to terminals 4c of bias coil 4 to provide a biasing flux to reed switch 2. Variable resistance 13 is serially connected with source 12 to selectively vary the level of biasing current and to provide the desired level of unfluctuating biasing flux. It can be seen that a steady biasing flux such as that provided by the circuit of FIG. 3b could also be supplied by a permanent magnet (not shown) rather than electromagnetic coil 4.

To illustrate the meaning of the operating characteristic curves, the operation of a relay under different conditions will be first explained with reference to FIG. 3a. Assume that no bias current is applied to coil 4 and initially there is no signal current. A signal current is then applied in the forward direction to terminals 8c or 10b and increased until the pick-up curve PU is intersected at approximately 40 ma. at which point the contacts 2b and 2c close. As the signal current is decreased, the contacts 2b and 2c remain closed until the drop-out curve DO is reached at approximately 13 ma., where contacts 2b and 2c open. Similarly, if a signal current of the opposite polarity or the reverse direction is applied, the

curves of the lower or reverse half of FIG. 3a indicate that contacts 2b and 2c will pick up at approximately 40 ma, and drop-out at approximately 13 ma.

Next assume that an unfluctuating D.C. bias current of 8 ma. is applied to coil 4 so that the relay operates along the vertical dashed line of FIG. 3 at 8 ma. and that, with no signal current, point A represents the condition of the relay. As a forward signal current is applied and increased, the operating point representative of the state of the relay proceeds upwardly along the dashed line. Contacts 2b and 2c remain open until the pick-up curve PU is reached at point B where contacts 2b and 2c close. At all points above the upper pick-up curve PU the contacts remain closed. As the signal current is reduced the contacts remain closed until point C on the drop-out curve DO is reached where the contacts open. Upon a reversal of the signal current the operating point passes through point A and proceeds downwardly with increased reverse signal current. Contacts 2b and 2c remain open until point D on the lower pick-up curve is reached. At all points below the lower pick-up curve the contacts remain closed. As the signal strength is reduced, the contacts remain closed until point E on the drop-out curve is reached.

It can be seen that the effect of the bias current is additive to that of forward signal currents and that the pick-up and drop-out characteristic curves therefore slope downwardly with increased biasing currents. A relay biased in the manner described is sensitive to the polarity of the applied signal current under certain circumstances. For instance, reference to FIG. 3a will show that the relay when biased with a current of 8 ma. will pick-up when subjected to a forward signal current of 40 ma. but will not pick-up when a signal current of the same magnitude but opposite polarity is applied.

It should also be noted that the curves for the prior art device in FIG. 3a substantially parallel one another and that the signal current differential between pick-up and drop-out is practically constant regardless of the bias current. Further, the magnitudes of signal current required for pick-up and drop-out cannot be varied independently.

Operating characteristic curves of the type shown in FIGS. 4a and 5a are obtainable from relays incorporating the present invention. FIG. 4a illustrates typical curves for a relay biased with a full wave rectified current from a rectifying bridge 16 as shown in FIG. 4b. Alternating current, preferably of 60 cycles per second, from source 14 is rectified by the full wave bridge 16 consisting of diodes 16a, 16b, 16c and 16d to supply to terminals 4c a pulsating full wave rectified current of the usual and well known wave form. Variable resistance 17 is serially connected with coil 4 so that a biasing current of the desired magnitude may be supplied to coil 4.

Consideration of the effects of several magnitudes of pulsating biasing current will serve to clarify the meaning of the curves shown in FIG. 4a. With zero bias current the operating points of the relay are, of course, the same as the operating points at zero bias current in FIG. 3a. With zero signal current and a bias current of 8 ma., point F represents the state of the relay. As a forward signal current is applied, the point representative of the state of the relay moves upwardly until at point G the relay picks up. At all points above point G the contacts 2b and 2c remain closed. When the signal current is reduced, the relay drops out at point H. Similarly, with a reverse signal current, the relay picks up at point J and drops out at point K. It should be noted that the differential between the pick-up and drop-out points decreases with increased bias current. Further, the forward drop-out current remains relatively constant with changes in bias level in comparison with the curve of FIG. 3a. With a reverse signal current, it is the pick-up current which remains relatively constant.

At higher bias current levels, due to the pulsating

nature of the biasing current, the contacts tend to open and close in a vibratory fashion under certain conditions. The crosshatched areas labeled VIB represent the areas in which this vibratory phenomenon occurs. FIG. 4a best illustrates typical relay operation in the vibratory regions. At a bias level of 16 ma., increase of the forward signal current will cause the relay to pick-up at point L without vibration. As the signal is decreased from point L the contacts 2a and 2b remain closed until, at point N, they begin to vibrate and open intermittently. As the signal current is further decreased, the vibration continues through the vibration area VIB until, at point P, the contacts remain open without intermittent closure caused by vibration of the contacts.

At slightly higher levels of bias current, a somewhat different type of operation occurs. For instance, at a bias current of 20 ma. when the signal current is increased in the forward direction above the zero level, the contacts remain open until a dashed line within the vibration area VIB is intersected at point Q. At point Q, the contacts approach one another to the extent that they intermittently close in a vibratory fashion. As the signal is further increased the contact continues to vibrate until at point R the vibration ceases and the contacts remain closed. If the vibration area VIB is approached from above point R, the decrease in signal current will cause the contacts to begin to vibrate open at point R. They will continue to vibrate when the signal current is further decreased through the vibration area VIB until point S is reached where the contacts remain open.

In the lower half of FIG. 4a, the vibration area VIB for reverse signal currents is inverted but is otherwise similar to that for forward signal currents.

FIG. 5a illustrates the effect of greater irregularity in bias current such as that provided by the half wave rectifier of FIG. 5b. The source 14 again preferably provides a 60 cycle per second alternating current. Rectifying diode 18 blocks alternate half cycles to furnish a half wave rectified current of well known wave form to terminals 4c. The magnitude of the rectified current may be selectively varied by variable resistance 19 in series with coil 4. The most significant effect of the decreased smoothness of wave form is that the pick-up curves PU and the drop-out curves, DO, approach each other more rapidly as the bias current is increased. Consequently, as FIG. 5a shows, the operation of the relay with half wave bias current is substantially the same as that shown in FIG. 4a for full wave bias current except that the similar effects of the pulsations in bias current occur with approximately half the average bias current required in FIG. 4a.

We claim:

1. A magnetically operated electrical switch assembly comprising:
electrical contact means having open and closed operating positions;
magnetic means energizable by application of magnetic flux to actuate said contacts;
a source of substantially steady magnetic flux applied to said magnetic means, said source of steady magnetic flux being energizable for operating said contacts between said operating positions;
a source of pulsating magnetic biasing flux applied to said magnetic means for urging said contacts toward one of said operating positions but of a magnitude insufficient alone to cause operation of said contacts, the strength of said source of pulsating flux being selected to cause operation of said contacts at a desired level of energization of said source of steady magnetic flux.
2. A magnetically operated electrical switch assembly comprising:
a magnetically operated switch of the reed switch type having contacts mechanically biased to an open position and magnetic means for actuating said contacts to a closed position upon application of sufficient magnetic flux to said magnetic means;

- a source of substantially steady magnetic flux for application to said magnetic means, said source of steady magnetic flux being energizable for actuating said contacts to the closed position;
- a source of pulsating magnetic biasing flux for application to said magnetic means of a magnitude insufficient alone to cause closure of said contacts;
- the strength of said pulsating magnetic biasing flux being selected to cause activation of said contacts at a desired level of energization of said source of steady magnetic flux.
3. A magnetically operated switch assembly comprising:
- a magnetically operated switch of the reed switch type having contacts mechanically biased to an open position and magnetic means for actuating said contacts to a closed position upon application of sufficient magnetic flux to said magnetic means;
- a source of substantially steady magnetic flux for application to said magnetic means, said source of steady magnetic flux being energizable for actuating said contacts to the closed position, the level of energization of said source of steady flux at which said contacts close being the pick-up point and the level of energization of said source of steady flux at which said contacts open being the drop-out point; and
- a variable source of unidirectional pulsating magnetic biasing flux for application to said magnetic means of a magnitude insufficient alone to cause closure of said contacts, variation of the strength of said pulsating biasing flux when the polarity of said pulsating biasing flux and said steady flux are of the same polarity, causing the pick-up point to decrease with an increased level of pulsating biasing flux while the drop-out point remains substantially constant, and

5

variation of the strength of said pulsating biasing flux when said pulsating biasing flux and said steady flux are of opposite polarity, causing the drop-out point to decrease with an increased level of pulsating biasing flux while the pick-up point remains substantially constant.

4. The invention as defined in claim 3 in which said source of unidirectional pulsating biasing flux comprises a coil supplied with electrical current from the unfiltered output of a half-wave rectifier.

5. The invention as defined in claim 3 in which said source of unidirectional pulsating biasing flux comprises a coil supplied with electrical current from the unfiltered output of a full-wave rectifier.
